UNITED STATES PATENT OFFICE.

THOMAS EDWARD KING, OF WESTFIELD, NEW JERSEY, ASSIGNOR TO HITCHINGS & COMPANY, OF ELIZABETH, NEW JERSEY, A CORPORATION OF NEW JERSEY.

SASH OPERATOR FOR GREENHOUSES.

Application filed November 4, 1924. Serial No. 747,730.

This invention relates to improvements in sash operator for greenhouses, and has for its object the provision of simple, efficient, and inexpensive means for overcoming the inertia and torsional strain of the usual sash operating shaft which simultaneously raises and lowers a bank of sashes therein.

Heretofore this shaft has been provided with a power device at one end thereof as well as counter-weights connected thereto, to assist the operator in raising the bank of sashes to open position and for sustaining the latter in open position against accidental closing. The arrangement just referred to did not, however, prevent some of the sashes from sagging, due to the torsional strain upon the shaft, and the present invention, in providing means for counter-balancing the weight of the sashes, overcomes the torsional strains referred to and accomplishes these results in a simple manner and gives assurance that the sashes will be simultaneously raised and lowered as the shaft is turned in the proper direction.

In the accompanying drawings Figure 1 is partly in section and partly in elevation, and shows my invention applied to the operating parts of one of the sashes;

Figure 2 is a plan view showing the invention applied to two of a bank of sashes.

Referring to the drawings which are merely illustrative of the invention, 1 designates the usual sash frame of a conventional greenhouse upon which are hinged a bank or banks of sashes 2, one of which is shown in the drawings hinged at 3 to the frame 1. A plurality of hangers 4 are severally secured to the rafters 4' and serve to support rotatably a sash-operating shaft 5, upon which is operatively secured, longitudinally, as many toggles as are required to raise and lower the sashes to open or closed position. The number of toggles required to each sash depends on the size of the latter; usually there are two toggles to a sash, and sometimes there are three. Each toggle consists of two arms 6 and 7, and these form a leverage to raise and lower the sashes, the arm 6 being connected hingedly at 8 to the outer end of the sash and the arm 7 being rotatably secured to the shaft 5, and both arms pivotably connected at 9. An elongated spiral spring 10 is secured at one end to the rafter 4' and at its opposite end is connected to the hook 11 of a lever or arm 12, fixedly secured to shaft 5. It will be understood that for each

sash there is mounted upon the shaft 5 a separate arm 12, the latter preferably projecting substantially at right angles to the arm 7.

In operation, when by proper actuating connections (not shown) the shaft 5 is manually turned or rotated (assuming the sash to be in closed position as shown in full lines in the drawings), the arms 6 and 7 move upwardly to the positions indicated in dotted lines, thereby raising the sash to its full open position. The spring 10 has a differential movement: (1) The force exerted by it when the sashes are closed and the arm 12 is in its full line position is nil, so far as concerns the rotation of the shaft 5 and its tendency to open the sashes, because the arm 12 is turned out of the line of force exerted by the spring; but (2) as the shaft 5 is rotated by the operator to raise the sashes, the arm 12 also rotates, and, moving downwardly, is brought into the line of force of the spring 10, thereby carrying the load for the operator over the most difficult part of the operation of opening the sashes.

It is obvious that with such a spring mechanism mounted on the shaft for each of the sashes, the torsional strain upon the shaft will be overcome, and an equal control will be secured upon the entire bank of sashes. It is important that there should be no accidental opening of the sashes when in closed position, and this is effectively provided against by turning the arm 12 into inoperative position, as above indicated.

Having described my invention, what I claim is:

1. In a device of the class described, the combination of a sash frame, a plurality of sashes movably connected thereto, a toggle connected to each sash, a shaft, each toggle being operated by said shaft to raise and lower said sashes, a rock-arm on said shaft, at each sash, an elongated spiral spring for each sash and being secured at one end to said frame and at the other end to said rock-arm, said rock-arm being so positioned as to carry said spring into inoperative position when said sash is closed and to carry it into operative position as said shaft is operated to open the sash.

2. In a device of the class described, the combination of a sash frame, a plurality of sashes movably mounted therein, a shaft extending continuously under said sashes, a link hingedly connected to each of said sashes,

arms rotatably mounted on said shaft, each having its extremity pivotally connected with each link, second arms carried by said shaft and arranged at an oblique angle with respect to said first mentioned arms and tensioning means fixed at one end to said frame and connected at its opposite end to the extremity of the second mentioned arms, said points of connection being alined above the longitudinal axis of said shaft when in inoperative position.

3. In a device of the class described, the combination of a sash-frame, a plurality of sashes hingedly mounted thereon, a continuous shaft adjacent thereto, means connected to said shaft and to said sashes for opening

and closing the latter on said frame, and differential spring mechanism connected to said shaft and to said sash-frame for counter-balancing the action of said sashes and so arranged that it is automatically shifted into inoperative position when said sashes are closed. 20

4. In a device of the class described, the combination of a sash-frame, a plurality of sashes mounted thereon, a shaft, means connected to said shaft and to said sashes for opening and closing the latter on said frame, and differential spring means connected to said shaft and to said sash-frame for counter- 30 balancing the action of said shaft.

T. EDWARD KING.
